UNITED STATES PATENT OFFICE.

CHARLES MILLER, OF LONG ISLAND CITY, NEW YORK.

ROTARY DRIER.

Application filed March 7, 1925. Serial No. 13,763.

This invention relates more particularly to a class of apparatus for depriving articles and materials of moisture.

My invention has for its object primarily to provide a drier of a rotative class designed for employing currents of air for drying footwear when moistened in the customary process of lasting the uppers, in order to save the time usually consumed by present methods used in the art of shoe manufacturing, and which also contemplates the employment of the drier for seasoning paper prior to being printed upon as well as being adapted for drying other articles and materials. The invention resides mainly in the provision of a rotatable chamber capable of holding articles for being dried by air, and the chamber has in its lower part an intake with its ingress passage extending in the direction of rotation of the chamber so that air will flow into the chamber when driven. In the upper part of the chamber is an outlet having its egress passage disposed away from the advancing passage of the intake, in order that the discharge of the air through the outlet will cause with the rotation of the chamber an effectual circulation for quickly extracting moisture from the articles within the chamber.

Other objects of the invention are to provide across the interior superposed racks each including spaced parallel bars with each bar having spaced lugs protruding therefrom toward the next adjacent bars for permitting the lasted uppers of footwear when moistened to be carried thereon in inverted positions; to provide power driven means for rotating the chamber; and to provide a rotary drier of a simple, efficient and durable construction which may be made in appropriate sizes and shapes.

With these and other objects in view, the invention will be hereinafter more fully explained with reference to the accompanying drawings forming a part of this specification in which similar characters of reference indicate corresponding parts in all the views, and will then be pointed out in the claims at the end of the description.

In the drawing, Figure 1 is an elevation of one form of rotary drier embodying my invention.

Fig. 2 is a top plan, partly sectional, of the drier.

Fig. 3 is a sectional view, partly in elevation, taken through the drier, and

Fig. 4 is a sectional view, partly in detail, taken on the line 4-4 of Fig. 3.

The drier has a casing 10 providing on its interior a chamber, and this casing or chamber may be of any suitable size and shape, though the form of the chamber shown has a cylindrical side wall 11, a bottom wall 12 and a top wall 13. In the side wall 11 is a door closed entrance 14. The chamber 10 is rotatably supported on a frame 15 which may be composed of an annular track or raceway 16 of a diameter approximately similar to the diameter of the chamber, and this track may be supported at a suitable height by a number of legs or standards, as 17. On the bottom wall 12 of the chamber are a number of spaced wheels 18 which are revolvable on the track 16 to enable the chamber to be freely rotated, and on the top wall 13 of the chamber may also be an upwardly protruding stud 19 which is journaled in a suitable bearing 20 provided on any appropriate support, as 21, above the chamber.

At the lower part of the chamber or leading through part of the lower end of its bottom wall 12 is an intake 22 for ingress of air into the chamber, and this intake is preferably somewhat of the form of a funnel shape pipe having a flared free end. This intake or pipe is curved to conform approximately to the curvature of the side wall of the chamber, and the pipe is disposed with flared ingress end in the direction of rotation of the chamber so that when the chamber is revolved the air admitted into the chamber through the intake will be partly compressed.

At the upper part of the chamber or leading through part of the upper end of its side wall 11 opposite to the intake 22 is an outlet 23 also preferably of somewhat the form of a funnel shape pipe having a flared free end. This outlet pipe is curved to conform substantially to the curvature of the side wall of the chamber, and the pipe is disposed with its egress end away from the advancing ingress end of the intake 22 for discharging

the air admitted through the intake into and circulated through the chamber during its rotation.

Within the chamber 10 are a number of spaced superposed racks 24 disposed across the chamber for supporting moistened lasted uppers of footwear, or other articles or materials for being dried. These racks may be similarly formed, and each rack includes a number of bars or rods 25 in spaced parallel relation, and each bar of each rack is provided with spaced fingers or lugs, as 26, 26^a, which protrude in opposite lateral directions toward the next adjacent bars. The bars of each rack are of relative lengths so that they terminate on a line corresponding to the curvature or shape of the side wall 11 of the chamber. The bars 25 of each rack are also of lengths so that the racks removably fit closely in the chamber, and the ends of the bars of the racks are supported upon annular brackets, or ledges or flanges, as 27, which are fixed in spaced superposed relation on the inner face of the side wall of the chamber. The bars of each rack are spaced from each other, and the lugs 26, 26^a are of lengths for spacing their free ends from the opposed lugs of the next adjacent bars to permit moistened lasted uppers, as A, of shoes to be removably supported therebetween in inverted positions, as shown, for subjecting the uppers to the drying influence of the currents of air circulated through the chamber.

The chamber 10 with its contents may be revolved by any appropriate means, though in the drawings I employ a form of mechanism, as 28. The mechanism 28 includes a bevel gear 29 which is fixed on the central part of the underside of the bottom wall 12 of the chamber. Meshing with the bevel gear 29 is another bevel gear 30 held on the drive shaft 31 of a motor 32 adapted to be driven from any suitable source of electrical energy, not shown, and the motor and shaft may be supported on a bracket, as 33, which is provided on one of the standards 17 of the frame 15. The bracket may be of somewhat a U-shape with one of its arms, as 34, carrying the motor, and on the other arm 35 of the bracket is a bearing 36 in which the central part of the shaft of the motor is journaled.

When the motor 32 is operated accordingly the shaft 31 will be driven to operate the miter gears 29, 30, and the chamber 10 with its contents will be rotated in a direction for causing air to be admitted into the chamber through the intake 22, and with the rotation of the chamber the air will be discharged through the outlet 23. As illustrated in the drawing, the outlet 23 is preferably positioned at an opposite part of the upper portion of the chamber to the position of the intake 22 for causing the currents of air to

circulate circuitously in the chamber before the discharge through the outlet for quickly and effectually drying the contents of the chamber.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:

1. In a drying apparatus, a rotatable chamber having a substantially cylindrical side wall, means providing only at the lower end of the wall an intake having its ingress passage extending in the direction of rotation of the chamber, and means providing only at the upper end of the wall an air outlet having its egress passage disposed away from the advancing intake whereby air will be caused to circulate in an upward circuitous course through the chamber.

2. The apparatus of the character set forth in claim 1, wherein the side wall is provided with a door for admitting articles into the chamber, wherein the elements are supported to travel on a track, and wherein the elements are provided with power driven means.

3. In a drying apparatus, a rotatable chamber having a substantially cylindrical side wall, an approximately funnel shape intake pipe leading into the lower end of the side wall with its flared ingress end disposed in the direction of rotation of the chamber for partly compressing the air admitted into the chamber, and an approximately funnel shape outlet pipe leading from the chamber through the upper end of the side wall with its flared egress end disposed away from the advancing ingress end of the intake pipe whereby air will be caused to circulate in an upward circuitous course through the chamber.

4. The apparatus of the character set forth in claim 3, wherein the side wall is provided with a door for admitting articles into the chamber, wherein the elements are provided with means to travel on a track, and wherein the elements are provided with power driven means.

5. A drying apparatus, comprising a stationary annular track supported at an elevation, a rotary chamber having a bottom wall, a cylindrical side wall and an upper wall, wheels mounted on the bottom wall of the chamber and revolvable on the track, a driven shaft, gearing on the bottom wall operative by the shaft for rotating the chamber.

ber, an approximately funnel shaped intake pipe leading into the lower end of the side wall with its flared ingress end disposed in the direction of rotation of the chamber for partly compressing the air admitted into the chamber, and an approximately funnel shaped outlet pipe leading through the upper end of the side wall with its flared egress

end disposed away from the advancing ingress end of the intake pipe whereby the air will be caused to circulate in an upward circuitous course through the chamber.

This specification signed this 6th day of March, A. D. 1925.

CHARLES MILLER.
